UNITED STATES PATENT OFFICE.

WILLIAM H. MALOY, OF SUFFERN, NEW YORK, ASSIGNOR TO AMERICAN BRAKE SHOE & FOUNDRY COMPANY, OF MAHWAH, NEW JERSEY, A CORPORATION OF NEW JERSEY.

BRAKE-SHOE.

1,198,251.

Specification of Letters Patent. Patented Sept. 12, 1916.

Application filed May 31, 1916. Serial No. 100,772.

To all whom it may concern:

Be it known that I, WILLIAM H. MALOY, a citizen of the United States, and a resident of Suffern, in the county of Rockland 5 and State of New York, have made and invented certain new and useful Improvements in Brake-Shoes, of which the following is a specification.

My invention relates to reinforcing backs 10 for brake shoes.

In forming backs with separate attaching lugs, it is customary to cut away the metal of the central portion of the back, and so reduce its width, so that the sides of 15 the lug which pass therearound may be spaced the proper distance apart. This construction results in a material reduction in the strength of the back.

It is therefore an object of the present 20 invention to provide a back wherein the reduction in width of the back at its center is accomplished without materially decreasing the strength of the back, and, in such manner, that an improved anchorage is provided for the attaching lug.

A further object is to provide a brake 25 shoe back which possesses the above-mentioned features, and, in addition is so constructed that the ends of the attaching lug 30 do not project below the general plane of the back, thus allowing the body of the shoe to be completely worn away without danger of severing the ends of the lug and destroying the anchorage between the lug and the 35 back.

Other objects and advantages will appear 40 as the description proceeds, wherein it is to be understood that changes in the precise embodiment of the invention can be made within the scope of what is claimed without departing from the spirit thereof.

The preferred embodiment of my invention 45 is disclosed in the accompanying drawings, wherein:

Figure 1 is a view in top plan of a brake shoe back embodying the characteristic features of my invention; Fig. 2 is a view in side elevation thereof; Fig. 3 is a view in central vertical section of a brake shoe, containing my improved reinforcing back; Fig. 4 is a bottom plan view of a central portion of the reinforcing back; Fig. 5 is a fragmental view in top elevation of a somewhat modified form of back, the toes 55 of the attaching lug in this instance being

bent sharply inward, beneath the reduced portion of the back; Fig. 6 is a view in section taken on the line 6—6 of Fig. 5.

Referring specifically to the several views, the reinforcing back 10 is provided with longitudinally extending, and spaced, openings 11 therein, these openings being enlarged at their ends, so that the removed metal forms an attaching lug with widening extremities.

In order to reduce the width of the back at its center without cutting the same, or in any wise weakening the back, the side edges are inwardly and upwardly bulged by pressing or stamping, the upset metal forming pockets 12, which are spaced slightly above the general plane of the back. The upward projection of these pockets results in the decrease in width of the back at its center, so that the sides 13 of the lug 14 are spaced the proper distance apart. The attaching lug 14 is preferably formed of ductile metal, and is provided with the widening ends 15, which seat within the pockets 12 whereby the lug is securely anchored to the back.

The body 16 of the shoe is cast around the back and lug 14, and aids in the securement between the lug and the reinforcing back.

In those instances where it is not desirable to provide a lug with widening extremities, the toes 17 of the lug are bent sharply inward, and are tucked beneath the upper and substantially flat walls 18 of the pockets.

The formation of the pockets, as above outlined, is accomplished without cutting or removing any of the metal of the back, so that the original strength of the back is preserved, while the upward extent of these pockets results in the decrease in width of the back and allows the extremities of the lugs to be anchored within the pockets without projecting below the general plane of the back.

What I claim is:—

1. A brake shoe back with the central side portions upwardly and inwardly bulged, and a lug with the ends thereof anchored within said bulged portions.

2. A brake shoe back provided at its edges with upwardly formed pockets, and a lug with widening ends anchored within said pockets.

3. A brake shoe back with a reduced cen-

tral portion and a lug with widening ends anchored within the reduced portion of said back.

4. A brake shoe back with the central side portions upwardly and inwardly bulged, and a lug with widening ends anchored within said bulged portions.

5. A brake shoe back with continuous side edges, the side edges of the back, at 10 their central portions, extending upwardly

and inwardly, forming spaced pockets and reducing the width of the back at its center, and a lug anchored within said pockets.

Signed at Suffern, in the county of Rockland and State of New York, this 24th day 15 of May, A. D. 1916.

WILLIAM H. MALOY.
